UNITED STATES PATENT OFFICE.

WILLIAM T. SHERMAN, OF TROY, NEW YORK, ASSIGNOR, BY MESNE ASSIGNMENTS, TO
HENRY L. HUGHES CO., INC., OF NEW YORK, N. Y., A CORPORATION OF NEW YORK.

BRUSH.

1,277,142.

Specification of Letters Patent. Patented Aug. 27, 1918.

Application filed January 4, 1916, Serial No. 70,269. Renewed February 25, 1918. Serial No. 219,157.

To all whom it may concern:

Be it known that I, WILLIAM T. SHERMAN, a citizen of the United States, residing at Troy, county of Rensselaer, and State of New York, have invented certain new and useful Improvements in Brushes, of which the following is a specification.

Reference may be had to the accompanying drawings, and the reference characters 10 marked thereon, which form a part of this specification. Similar characters refer to similar parts in the several figures therein.

The invention relates to a type of toilet-brush in which the bristles are supported by an elastic pad or sheet which is inserted and secured in a recess in the brush-back, and preferably so confined by the walls of the recess that the pad is held in a buckled position so as to present an outwardly 20 curved or convexed surface from which the bristles divergently project.

The principal object of the present invention is to tightly secure the edges of the pad within the recess in the brush-back.

25 Other objects will appear in connection with the following description.

Figure 1 of the drawings is a plan view of the face of a brush embodying my invention, with a portion of the bristle-supporting 30 pad broken away, and an edge-portion of the pad and the wall of the recess in the brush-back shown in horizontal section.

Fig. 2 is a plan view of the opposite side of the brush with the brush-back partly cut 35 away and shown in horizontal section.

Fig. 3 is a vertical cross-section of the brush taken on the broken line 3-3 in Fig. 2.

Fig. 4 is a vertical cross-section of the 40 brush taken on the broken line 4-4 in Fig. 2.

Fig. 5 is a central, vertical longitudinal section taken on the broken line 5-5 in Fig. 2.

45 Fig. 6 is a plan view of the clamp-plates and the operating wedge separated from one another.

Referring to the drawings wherein the invention is shown in preferred form, 1 represents the brush-back formed with a recess, 2, of a form and size adapted to receive the bristle-supporting pad, 3, the edge-portion of which closely fits within the recess.

The bristles, 4, may be attached to the pad, 55 3, in any known manner.

The pad is formed of elastic material, preferably soft rubber, and is preferably of such a size that when its edge-portion has been forced into the recess, 2, in the brush-back, the pad will be buckled or curved outwardly, presenting a convexed outer surface from which the bristles divergently project.

In the drawings a preferred form of recess is shown, the wall of which is undercut to form a groove, 5, well adapted to receive 65 the inserted edge of the pad.

In carrying out my invention, I inclose between the pad and the brush-back, clamping-mechanism co-operative with the wall of the recess to clamp thereagainst the edge- 70 portion of the pad.

In the preferred form of my invention shown, this clamping-mechanism comprises a pair of relatively movable clamp-plates, 6, and a movable wedge, 7, interposed between 75 said clamp-plates.

The outer edge-portions of the clamp-plates, 6, conform approximately to the contour of the side wall of the recess against which the inserted edge-portion of the pad 80 rests, and serve, when the clamp-plates have been forced apart by the wedge, to securely clamp the edge-portion of the pad against the wall of the recess.

The clamp-plates and wedge may be 85 made of wood, metal or other suitable material, but I prefer to make the clamp-plates of wood, and the wedge of metal; and to form on opposite sides of the wedge a series of teeth, 8, which become embedded in the 90 edges of the wooden clamp-plates when the wedge is driven in between them and thereby effectively prevent withdrawal of the wedge.

The wedge is preferably provided with a 95 longitudinal slot, 9, through which one or more headed nails or pins, 10, are driven into the brush-back, forming a loose guide for the wedge in its movement, and retaining the wedge in connection with the brush-back while the pad is being inserted and clamped within the recess.

In completing the brush, the clamps, 6-6, are laid within the recess in the brush-back on opposite sides of the wedge which is 105 withdrawn sufficiently to leave a suitable space between the outer edges of the clamp-plates, and the side wall of the recess into which space the edge-portion of the pad is inserted, after which the edge is driven in 110

between the clamp-plates by means of a pin or other suitable tool, 13, inserted through a perforate opening, 11, formed in the wall of the recess, which opening may also serve 5 as a vent-opening when the brush is in use.

When the wedge has been well driven in between the clamp-plates, the clamp-plates will be so spread apart that their outer edges will tightly clamp the edge-portion of 10 the pad against the wall of the recess, not only securely retaining the pad in position, but making a practically water-tight joint between the pad and the brush-back.

To facilitate the action of the wedge, the 15 clamp-plates may have formed on their inner edges, where engaged by the wedge, inclined surfaces, 12, corresponding with the taper of the wedge.

The ends of the clamp-plates are preferably cut away or rabbeted as at 14, to permit the plates to lap one another at their ends so as to make contact with the edge-portion of the pad throughout the extent 20 of its internal periphery.

25 The walls of the recess, 2, may be of any form suitable for properly supporting the edge of the pad in opposition to the thrust of the inclosed clamping-mechanism; and various changes in the form of the inclosed 30 clamping-mechanism are possible without departing from the spirit of my invention.

I make no claim herein broadly to means 35 inclosed between the pad and the brush-back coöperative with the wall of the recess to secure the edge-portion of the pad within the recess as this feature is generically claimed in my copending application Serial Number 115,951, filed August 21, 1916, for brush, and which application is for cer-

tain purposes of the invention a continuance 40 of the present application.

What I claim as new and desire to secure by Letters Patent is—

1. A brush having a back provided with a recess, and an elastic bristle-supporting 45 pad the edge-portion of which fits within said recess, and having inclosed between the pad and the brush-back an expansible clamp coöperative with the wall of the recess to clamp thereagainst the edge-portion of the 50 pad, and a clamp-expanding member.

2. A brush having a back provided with a recess and with a perforate opening through a wall of the recess, and an elastic bristle-supporting pad the edge-portion of 55 which fits within said recess, and having inclosed between the pad and the brush-back an expansible clamp coöperative with the wall of the recess to clamp thereagainst the edge-portion of the pad, and a clamp-expanding member accessible for operation through said perforate opening.

3. A brush having a back provided with a recess and with a perforate opening through a wall of the recess, an elastic bristle-supporting pad the edge-portion of which fits within the recess, and clamping-mechanism inclosed between the pad and the brush-back comprising relatively movable clamp-plates coöperative with the wall of the recess to clamp thereagainst the edge-portion 65 of the pad, and a movable wedge interposed between the clamp-plates and accessible for 70 operation through said perforate opening.

In testimony whereof, I have hereunto set 75 my hand this 30th day of December, 1915.

WILLIAM T. SHERMAN.
